GAUGING APPARATUS FOR LIQUID CONTAINERS

John H. Wiggins, Chicago, Ill.

Application November 5, 1937, Serial No. 172,936

8 Claims. (Cl. 137—18)

This invention relates to devices of the kind that are used on liquid storage tanks and other containers for enabling the tank to be gauged and for permitting a sample of the stored liquid to be removed from the tank for testing purposes.

The main object of my invention is to provide a gauging apparatus for storage tanks that comprises a gauge well located inside of the tank and a means of novel construction for establishing and cutting off communication between said well and the space in the tank in which the liquid is stored, whereby liquid may be trapped in the well for gauging or test purposes, or free and unobstructed circulation of the liquid from the well to the tank and vice versa may be established. Other objects and desirable features of my invention will be hereinafter pointed out.

Figure 1 of the drawing is a fragmentary vertical sectional view illustrating my invention applied to a liquid storage tank provided with a stationary roof or top.

Figure 2 is a fragmentary side elevational view of the tank showing the parts of my improved gauging apparatus that are arranged on the exterior of the tank.

Figure 3 is an enlarged fragmentary view partly in elevation and partly in section, illustrating the water passageway at the lower end of the gauging well and the lowermost oil passageway for establishing communication between the well and the interior of the tank.

Figure 4 is a sectional view illustrating how my invention may be applied to a liquid storage tank provided with a breather type roof; and

Figure 5 is a detailed view illustrating how the passageways extending from the tank to the gauging well may be constructed in the event it is desired to have an apparatus whose control valves may be removed for inspection, repair or replacement without taking the tank out of service.

In the accompanying drawings which illustrate the preferred form of my invention, A designates a container such, for example, as a metal tank that is used to store oil; B designates a stationary roof for said tank that protects the contents of the tank from the atmosphere. C designates a gauging well arranged preferably inside of the tank and provided at its upper end with a removable gas-tight cover carried by a manually operable operating device; 2; 3 designates a series of passageways, hereinafter referred to for convenience as oil passageways, that are arranged at different levels throughout the height of the well; C; 4 designates a water passageway at the extreme lower end of the gauging well which leads to the extreme lower end of the tank; and 5 designates a gas passageway at the upper end of the tank which leads to the upper end of the gauging well. The oil passageways 3 above referred to are used to permit the oil or other liquid stored in the tank to

circulate into and out of the gauging well and are arranged sufficiently close together so as to insure that the liquid will normally stand in the gauging well at the same height or level as the liquid in the tank; the water passageway, of course, being used to permit water to pass from the tank into the gauging well and stand at the same height therein as the water at the bottom of the tank, and the gas passageway 5 being used to establish or maintain a corresponding pressure in the upper end portions of the well and tank.

Control valves D are arranged in the oil passageways 3 and control valves E and F are arranged in the water passageway 4 and gas passageway 5, respectively, so as to establish and cut off communication between the interior of the tank and the interior of the gauging well through the said passageways, the said valves being combined with an operating mechanism arranged on the exterior of the tank so as to enable said valves to be opened and closed easily. The valves D, E and F preferably consist of lubricated plug cocks and the stem of each of said valves is provided with a cross arm 6 whose opposite ends are pivotally connected at 7 to operating links 8 as shown in Figure 2; whereby all of the valves may be moved in unison to open or close the same. The gauging well C is preferably formed by a relatively large metal pipe, say from six to eight inches in diameter, arranged vertically inside of the tank A adjacent the side wall of same and having its lower end connected by a tight joint to the bottom of the tank. The upper end portion of the pipe which constitutes the gauging well projects upwardly through the roof B of the tank and is connected to same by a gas-tight joint, the removable cover of the gauging well being located on the exterior of the tank as shown in Figure 1. While the specific details of construction of the passageways that establish communication between the tank and the gauging well are not essential so far as my broad idea is concerned, I prefer to provide each of the oil passageways 3 with a vertically disposed portion in which the control valve is located and connect the lower end of said vertically disposed portion by a lateral branch with the interior of the tank and connect the upper end of said portion by a lateral branch with the interior of the gauging well, so as to insure a constant circulation between the tank and the gauging well due to the thermosyphon action set up by the vertical runs in the passageways 3 and the difference in temperature of the liquid in said vertical runs from the temperature of the liquid in the tank.

When all of the control valves are open, the gas and liquid pressure inside of the well C is exactly the same as in the tank A; therefore, the liquid level inside the well is exactly the same as the liquid level inside the tank. Also, a true average

sample of the liquid in the tank is in the well C because the passageways 3 are arranged close enough together to attain this end. Moreover, there is a constant circulation between the tank 5 and the well due to the thermosyphon action as previously explained. By varying the length of the vertically disposed portions of the oil passageways 3 the thermosyphon effect can be varied to meet existing conditions. When all of the valves 10 D, E and F are shut, then the liquid height in the well C cannot change because it is trapped from the liquid and internal gas pressure. Accordingly, it is possible to open the cover 1 at the upper end of the gauging well and release any pressure 15 or vacuum inside the well without changing the liquid height in the well and, moreover, without danger of losing any vapor from the tank. The tank can now be gauged in the well and later sampled from the well. Although the thermosyphon effect will carry oil of a slightly different 20 temperature from the tank to the gauging well, the volume of this is so slight compared to the volume in the well and, furthermore, there is such a rapid interchange of heat between the well and 25 the contents of the tank, that any difference of temperature between the liquid in the tank and in the gauging well is negligible and much less than is practical to measure.

In an apparatus of the construction above described, the tank can be gauged without exposing the contents of the tank to the air and other advantages of such an apparatus are that it insures an average sample of the contents of the tank in the gauging well, it permits a test sample 30 to be removed without the necessity of measuring the internal pressure of the tank, it enables the gauging well to be positively cut off from the tank simply by operating a mechanism located in the exterior of the tank and, as the control valves D, E and F are arranged on the outside of the tank, they may be easily checked, lubricated or adjusted. If desired, the apparatus can be constructed so that the control valves can be entirely removed and replaced by other 35 valves while the tank is in service, such an apparatus being illustrated in Figure 5 of the drawing, wherein each of the passageways between the tank and the gauging well C is equipped with two manually operable auxiliary valves 9 and 10 arranged on opposite sides of the control valve in the passageway.

In Figure 4 I have shown how my invention may be applied to a tank A provided with a breather type roof B' that is adapted to flex 55 vertically upwardly and downwardly to vary the volume of the vapor space of the tank. When my invention is applied to such a tank, the gauging well C projects upwardly through a hole 11 in the roof of the tank that is surrounded by a 60 collar 12, said collar 12 being joined by an annular-shaped element 13 made of weather and oil proof fabric to a flange or collar 14 on the exterior of the vertically disposed pipe that constitutes the gauging well C. In all other respects 65 the apparatus shown in Figure 4 is the same as that shown in Figure 1.

Having thus described my invention, what I claim as new and desire to secure by Letters Patent is:

70 1. In a liquid storage apparatus, the combination of a container for holding the liquid, a

gauge well located inside of the container and a plurality of passageways arranged at different levels on the exterior of the container, each of said passageways having a portion that communicates with the interior of the container and a portion that extends through the side wall of the container and communicates with the interior of the well. 5

2. A liquid storage apparatus comprising the combination of elements specified in claim 1, plus 10 a removable closure for the well that establishes atmospheric pressure in the well when said closure is open. 10

3. A liquid storage apparatus of the kind described in claim 1 equipped with a manually operable means for initiating and cutting off circulation of the liquid from the container to the well and vice versa. 15

4. A liquid storage apparatus comprising a container for holding the liquid, a gauge wall, 20 and a plurality of passageways located at different levels for establishing communication between said container and well, said gauge well being located inside of the container and a majority of said passageways having vertical portions 25 located on the exterior of the container. 25

5. An oil storage apparatus comprising a container or tank for holding the oil, a gauge well on the interior of the tank provided with a removable closure operable from the exterior of the tank, means for permitting the oil in the tank to circulate from the tank to the well or vice versa at a plurality of different points along the height of the well, a water passageway extending below the bottom of the container for establishing communication between the extreme lower end of the well and the bottom of the container, a gas passageway leading from the upper end portion of the container to the upper end portion of the well, and a control means for 40 said passageways. 35

6. A liquid storage apparatus comprising a tank for holding the liquid, a vertically disposed gauge well in said tank projecting upwardly through the roof of the tank and provided at its upper end with a means which provides access to said well, passageways on the exterior of the tank communicating with the interior of the tank and with the interior of the well for causing the well to be normally charged with liquid 50 which stands at the same level as the liquid in the tank, the upper portion of the tank being connected by a gas duct with the upper portion of the well, and means operable from the exterior of the tank for positively preventing circulation of any liquid or gaseous medium from the tank to the well or vice versa, preparatory to the operation of gauging the tank or removing a test sample from the well. 55

7. An apparatus of the kind described in claim 6, in which the passageways on the exterior of the tank are located at different levels and each passageway comprises a vertically-disposed portion. 60

8. A liquid storage apparatus of the kind described in claim 6, in which the roof of the tank is of the breather type and the gauge well is stationarily mounted and is joined with the roof by a gas-tight connecting element which permits the roof to move relatively to the well. 65
